CARBURETOR

Milton E. Chandler, Detroit, Mich.

Application January 21, 1935, Serial No. 2,682

9 Claims. (Cl. 261—44)

Object of this invention is to design a carburetor of a novel form which will have distinct advantages over carburetors now in use. The carburetor will lend itself particularly well to the requirements of aircraft engines and to the requirements of the high efficiency engines that are now being used.

Carburetor design has in the past followed more or less distinct trends. For a time the popular carburetor in use had fuel orifices of fixed size and the air openings automatically variable as a function of air flow through the carburetor. Later variable fuel orifices were used with the automatically variable air openings. It was difficult with these carburetors to obtain maximum torque owing to the restriction of the air valve and likewise to the fact that the air passages were not of uniform cross-section and the distribution of air and fuel was bad. Later this type of carburetor was replaced in popularity with carburetors of a so-called plain tube type having a fixed air orifice and a fixed fuel orifice. These carburetors were and are very popular and efficient, but as engine output per cubic inch increased the air orifice became so large that it was difficult to get good flexibility on account of the low suction on the fuel nozzle at low air flows and it was necessary to add various devices to cover up the inherent deficiencies of this type of carburetor. The plain tube carburetors, the same as the air valve carburetors, likewise had air passages that were not uniform in cross-section and trouble has likewise been encountered in getting good distribution and power. The conventional butterfly throttle between the fixed air orifice and the intake manifold likewise contributed to poor distribution at some throttle openings.

In this invention the air openings will be mechanically variable as a function of the power demanded and the fuel orifice will likewise be variable as a fixed function of the position of the air opening. The ordinary throttle is dispensed with and the variation in the opening of the air passage mechanically controlled constitutes the only control of air opening or throttling. In this invention the air openings or passageways are symmetrically arranged on either side of a vertical plane longitudinal with the carburetor or a vertical plane crosswise with the carburetor. The air will therefore always at all throttle openings travel a uniform path and will not be deflected by non-uniform sections of the air passage.

The carburetor will meter as a plain tube carburetor for every position of the Venturi throttles, for at every position of the throttle there is a proper size of fuel orifice to correspond therewith. The fuel is always discharged through one discharge nozzle and the lag that occurs in transferring from the idle in the plain tube

carburetor to the main jet will not be evident. The present so-called plain tube carburetors mechanically meter during the idle range and up to about twenty-five miles per hour. This mechanical metering is crude and difficult to control. At speeds above twenty-five miles an hour and up to about seventy miles per hour the metering is primarily a function of air flow and beyond this and up to maximum speed it is a combined function of air flow and mechanical means. With the new design the fuel ratio is mechanically controlled for every throttle position in a simple and accurate manner. For a given throttle position and a variable air flow it will meter purely as a function of air flow. These characteristics will make it easy to obtain the desired air and fuel mixture ratios.

Figure 1 is a cross-sectional plan view taken on plane 1—1 of Figure 2.

Figure 2 is the end view of Figure 1.

Figure 3 shows the cross-sectional elevation taken on plane 3—3 of Figure 2, but showing the construction shown in Figure 1 modified so as to produce a duplex construction.

Figure 4 is a cross-sectional elevation taken on plane 4—4 of Figure 1.

Figure 5 shows a detail of the nozzle control for the construction shown in Figure 3.

Figure 6 shows an alternative method of controlling the fuel flow. Fig. 7 shows an elevation on plane 7—7 of Figure 3.

Describing the embodiment of my invention shown in Figures 1, 2 and 4, the air entrance is shown at 10 surrounded by walls 40 and the mixture outlet is shown at 11. Two cylindrical throttles 12 and 13 mounted on bearings, located in end walls 41 and 42, are shown geared together with a set of gears 16 and 17 and adapted to engage with a horizontal fuel passage 27, so as to provide two rectangular openings on each side of the passage 27.

The fuel supply to a fuel passage 20 is obtained through a vertical passage 19 which communicates with a float chamber 18, the float-mechanism details of which are not shown.

The fuel supply is regulated by means of a restriction 21 and a needle valve 22, both mounted in the passage 20. The needle valve 22 is moved in unison with the movement of the two throttles 12 and 13 by means of a cam 24 which engages with a lever 23, which is pivoted to an end wall 42 of the carburetor, on a pin 33 mounted in the wall 42, the lever 23 engaging with the needle valve 21. A spring is mounted in the passage 20 and its function is to take up any backlash there may be in the mechanism. The fuel flows from the upper fuel passage 20 through the restriction 21, to the lower fuel passage 27, through a cross passage 26. The lower passage 27 is perforated at 28 to provide fuel outlets into the mixing cham-

ber. Fuel thus issues into the throat of the variable venturi of rectangular form, between the throttles 12 and 13 and the transverse horizontal fuel passage 27.

5 Describing next the duplex construction shown in Figures 3 and 5, the cylindrical throttle 13 is provided with a web 34 which divides the venturis into two. The mixture outlet 11 is divided into two equal rectangular portions 11'-11'', by 10 means of a vertical wall 30. This wall 30 is in alignment with the web 34. The two mixture outlets 11'-11'' are thus separated by the web 34 on the throttle 13 and, of course, a corresponding web, not shown, on the corresponding throttle 12.

15 In Figure 3 the fuel discharges past the restriction 21, and is assisted by an air vent 35, located in the air entrance 10, which admits a jet of air, which sweeps over the restricted outlet from the 20 orifice 21, and discharges atomized fuel and air through the passage 26 into the horizontal passage 27, which discharges into the throat of the two venturis through the outlets 28 and 29.

Figure 5 shows a modification of the air vent 25 35. A spring loaded air valve 25 is used to restrict the flow of air which mingles with the fuel issuing from the restriction 21 and flowing through the communicating passage 26 into the horizontal fuel passage 27, whence the fuel and air is discharged as before through the outlets 28 and 29.

30 In Figure 6 a sylphon bellows 31 is shown located between the needle 22 and its operating lever 23. A passage 32 in the center of the needle 22 admits the depression or vacuum in the fuel manifold 27 to the interior of the sylphon bellows 31, whereby the fuel restriction 21 is automatically closed when an excessive suction is transmitted from the mixing chamber around the manifold 27 through the orifices 29 and 28 and through the 40 orifice 26 to the interior of the bellows 31. By this means compensation is obtained at high air flows to prevent an excessively rich mixture which would otherwise be formed due to the fact that air is an elastic medium and liquid gasoline 45 is not.

What I claim is:

1. A carburetor comprising a symmetrical mixture outlet, a symmetrical air entrance located on the same axis as said outlet, two symmetrical 50 rollers having parallel sides adapted to roll together so as to act as throttles and also to form a variable symmetrical rectangular mixing chamber of Venturi form located between said air entrance and said mixture outlet and having an 55 axis parallel to the axis of said air entrance, a fuel nozzle located so as to discharge at all times into the throat of said variable rectangular venturi, a needle controlled by the movement of said rollers and adapted to control the flow of 60 fuel to said nozzle, and means controlled by the depression in said venturi for moving said needle independently of said rollers.

2. A duplex carburetor having two similar rectangular air passages controlled by two similar 65 cylindrical throttles adapted to roll together so as to act as the throttles and also to form two variable rectangular Venturi openings therebetween, a common fuel passage, a source of fuel supply leading thereto, a restriction in said passage, a second fuel passage connected thereto beyond the point of restriction therein, said second fuel passage extending transversely across 70 said Venturi openings, a plurality of fuel outlets

discharging into the throats of said Venturi openings.

3. A carburetor comprising a carburetor body, a pair of streamlined symmetrical rollers mounted therein, the surfaces of which are parallel to their axes, means for rotating them together so as to form a variable Venturi opening of rectangular construction therebetween in said carburetor body, fuel supply means, a main fuel discharge passage connected thereto and extending completely across said variable Venturi opening on an axis parallel to the axes of the two rollers and located symmetrically with reference thereto so as to divide the throat of the venturi into two equal and similar rectangular openings, and lateral fuel outlets from said fuel passage discharging into the throat of each of said rectangular Venturi openings at its point of minimum area. 15

4. A carburetor as defined in claim 3, in which the flow of fuel in said fuel passage is controlled 20 by a needle valve operated in unison with said rollers.

5. A carburetor comprising a carburetor body, a pair of symmetrical rollers, the surfaces of which are parallel to their axes, mounted therein, 25 means for rotating them together so as to form a variable Venturi opening of rectangular construction therebetween in said carburetor body, fuel supply means, a fuel passage leading therefrom, a restriction therein, a second fuel passage 30 connected to the first fuel passage on the downstream side of said restriction and extending completely across the Venturi opening on an axis parallel to the axes of the two rollers and located so as to divide the throat of the venturi into 35 two equal and similar rectangular openings, and lateral fuel outlets from said second fuel passage discharging into the throat of each of said rectangular Venturi openings at its point of minimum area. 40

6. A carburetor as defined in claim 5 with an atmospheric opening into said first fuel passage adjacent to said restriction and adapted to aspirate the fuel issuing therefrom.

7. In a carburetor, a mixture chamber, a mixture outlet, an obstruction having a fuel passage therein extending transversely across the center of said mixture chamber, throttle means located in said chamber on each side of said obstruction and engaging therewith so as to form two variable 50 mixture openings between the obstruction and the throttles, said openings forming at all times the sole restriction to the flow of mixture through said carburetor, an unobstructed passage connecting said sole restriction with the mixture 55 outlet, and lateral fuel outlets from said fuel passage into said variable mixture openings. 45

8. In a carburetor as set forth in claim 7, a stationary transverse partition separating the mixture chamber into independent equal halves, 60 and movable partitions mounted on said throttles in alignment with said stationary partition for the purpose described.

9. In a carburetor as set forth in claim 7, means for dividing the mixture chamber into a 65 plurality of separate independent mixture chambers of equal area, said means including at least one stationary partition arranged transversely to the axis of the throttles and at least two movable partitions for each stationary partition mounted 70 on said throttles in alignment with said stationary partition separating the mixture chamber into a plurality of independent equal portions.

MILTON E. CHANDLER.
